POWER TRIMMER FOR LAWNS, HEDGES AND THE LIKE

Loren J. Ellison, Salt Lake City, Utah, assignor to Dun-
field-Durkee, Inc., a corporation of Utah

Application December 27, 1957, Serial No. 49,046

Term of patent 14 years

(Cl. D40—1)

FIG. 2

FIG. 3

FIG. 1

Figure 1 is a side elevational view of a power trimmer for lawns, hedges and the like, showing my new design; Figure 2 is a front elevation thereof;

Figure 3 is a rear elevation thereof;

Figure 4 is an enlarged, top plan view thereof, the handle being broken away for convenience of illustration;

Figure 5 is an enlarged, bottom plan view thereof, the handle being removed for convenience of illustration; and Figure 6 is a perspective view thereof.

I claim:

The ornamental design for a power trimmer for lawns, hedges and the like, substantially as shown and described.
